SOAP HOLDER

Mordicha Margolish, Hawthorne, Calif.

Application August 3, 1936, Serial No. 94,105

8 Claims. (Cl. 45—28)

This invention relates to a device for handling soap, or the like, and relates more particularly to a soap holder for handling soap in the form of a bar or cake. A general object of the invention is to provide a device or soap holder of the character mentioned that is particularly easy and convenient to use and that is effective and dependable in holding the soap.

Bar soap or cake soap as used in lavatories, washrooms and the like is usually contained in soap dishes or trays. Such soap dishes and trays are not entirely satisfactory, in that they do not allow the soap to properly drain off or dry. When the soap is not allowed to dry properly it becomes soft and partially liquifies. This makes the soap and the dish or tray carrying it very slippery and unsanitary. The soap in this condition is unpleasant and inconvenient to use and a large part of the soap is wasted.

Another object of the present invention is to provide a device that effectively holds a bar or cake of soap in such a manner that its entire surface is exposed to the air, so that the soap quickly dries. The device in allowing the soap to properly and quickly dry makes the soap pleasant and clean to handle and provides for economy in its use.

Another object of this invention is to provide a soap holder of the character mentioned that effectively supports a cake of soap in a position that permits the user to remove or insert the soap without coming into contact with the soap holder.

A further object of the present invention is to provide a device of the character mentioned that dependably holds a cake of soap in such a manner that the soap is free to be grasped and then lifted, which releases the engagement of the holder with the soap, allowing its ready removal.

Another object of the present invention is to provide a soap holder that does not require careful placing of the cake of soap, as the soap holder will dependably grip and retain the cake of soap regardless of the particular points on the cake of soap engaged or gripped by the holder.

A further object of the present invention is to provide a soap holder of the character mentioned that will effectively hold cakes of soap of various sizes and shapes, thus giving the soap holder an unlimited range of effectiveness.

Another object of the present invention is to provide a device of the character mentioned that is small and compact, requiring a minimum

amount of space and that is inconspicuous and slightly in appearance.

A further object of the present invention is to provide a device that is constructed of but few small sturdy parts which makes it very simple and inexpensive of manufacture.

The various objects and features of my invention will be fully understood from the following detailed description of a typical preferred form and application of my invention, throughout which description reference is made to the accompanying drawing, in which:

Fig. 1 is a front elevation of the device or soap holder provided by this invention illustrating it carrying a cake of soap. Fig. 2 is a top or plan elevation of the device. Fig. 3 is a side or end elevation of the device. Fig. 4 is a vertical detailed sectional view taken as indicated by line 4—4 on Fig. 3, and Fig. 5 is an enlarged fragmentary vertical detailed sectional view taken as indicated by line 5—5 on Fig. 4.

The improved soap holder of my invention includes, generally, a bracket or body 10, gripping members or elements 11 carried by the body 10 and adapted to receive a cake of soap S, and means 12 for controlling movement of the gripping elements 11.

The bracket or body 10 may be varied considerably in shape and form without departing from broader aspects of the invention. The body 10 illustrated in the drawing is a simple, one piece stamping or member that is subsequently rectangular in front elevation. The body 10 has a main portion or outer face portion 15 which may lie in a substantially vertical plane and inwardly projecting upper and lower flanges 16, integrally joined to the outer face portion 15. The flanges 16 may be in planes substantially normal to the plane of the portion 15. A strap or plate 17 is received between the flanges 16. The plate 17 may be secured to the flanges 16 in any suitable manner. For example, it may be welded or soldered to the flanges 16. The plate 17 received between the flanges 16, as illustrated, provides a space in the body for housing the means 12 and various parts of the device to be hereinafter described. The plate 17 has lugs or ears 18 projecting from the opposite ends of the body. The ears 18 provide means for mounting the device on a suitable support. To simplify the construction the ears 18 are preferably integral continuations of the plate 17. The ears 18 may be attached to a suitable support, such as a wall, post, panel, or the like, to render the device convenient and readily accessible for

45

50

55

55

use. The ears 18 illustrated in the drawing are provided with openings 19 for receiving screws or the like for removably mounting the device. The invention also contemplates the permanent 5 cementing or securing of the device to a support, if desired.

The gripping elements 11 for holding a cake or bar of soap S may be varied somewhat without departing from the spirit of the invention. The 10 gripping elements are in the form of two members carried by the body 10 for relative movement. In the preferred construction the elements 11 are similar in shape and configuration and are paired or complementary. The elements 11 may be 15 formed from round stock and are substantially L-shaped in their general configuration each having branches 20 and 22. The branches 20 of the elements 11 project outwardly from the face portion 15 of the body 10 adjacent its opposite ends. 20 The branches 20 of the elements 11 are pivotably carried in openings 21 in the face portion 15 of the body and project outwardly a substantial distance before joining the branches 22. The outer branches 22 of the elements 11 have their longitudinal axes substantially normal to the longitudinal axes of the branches 20 and normally project upwardly and toward one another, as best 25 illustrated in Fig. 1 of the drawing. The outer ends of the branches 22 are bevelled, as at 20a, to form points or tips which are adapted to effectively grip and hold the cake of soap S.

The invention provides means for supporting the outer end portions of the branches 20. Outwardly projecting arms 23 are provided at the 30 opposite ends of the body 10 to assist in pivotably supporting the elements 11. The arms 23 are preferably formed integral with the body 10. In the drawing I have illustrated the arms 23 integral with the face portion 15 of the body and bent at right angles to the portion 15 to project outwardly from the ends of the body. The arms 23 may be parallel with the branches 20 and have angular portions 24 at their outer ends. The angular portions 24 of the arms 23 are provided 35 with openings 25 for pivotably receiving the branches 20 to aid in supporting the elements 11. The elements 11 are shiftable from a normal position where their tips 20a are adjacent one another, as illustrated in Fig. 1 of the drawing, to a position where they are spaced some distance 40 apart, to allow the cake of soap S to be readily gripped by the tips of the branches 22. When the elements 11 are in their fully opened or extended positions the branches 22 are related so that there is sufficient clearance between them to readily receive a cake of soap of the size or 45 character within the range that the device is intended to handle.

The means 12 for controlling the pivotal movement of the elements 11 includes arms 26 secured to the inner ends of the branches 20. The arms 26 may be secured to the branches in any suitable manner. In the drawing I have illustrated the arms 26 pressed onto reduced portions on the inner ends of the branches 20. To insure rigid connections between the arms 26 and the elements 11 the reduced portions of the branches 20 may be hammered or peened over. The arms 26 are within the space in the body 10 and are 50 adapted to freely shift or swing. The arms 26 project upwardly and inwardly toward one another and are preferably longitudinally curved as best illustrated in Fig. 4. Washers 27 may be provided on the branches 20 to space the arms 26 from the body portion 15. The arms 26 are pivot-

ally and shiftably connected to operate in unison. A longitudinal slot 40 is provided in the upper portion of one arm 26 and a headed pin 41 is secured to the other arm to operate in the slot. A washer 42 on the pin 41 may retain the arms 26 in spaced relation. The slot 40 is preferably longitudinally curved to effect a more uniform motion of the arms 26. It is believed that it will be apparent how the pin 41 operating in the slot 42 effects simultaneous pivoting of the arms 26 and elements 11.

The means 12 for controlling movement of the elements 11 preferably includes a spring means for urging the branches 22 of the elements 11 into gripping engagement with the cake of soap S. In practice this spring means may comprise a single spring 30. The spring 30 may be any suitable type of spring. For example, it may be a leaf spring, helical spring, or a simple piece of spring wire as I have illustrated in the drawing. The spring 30 illustrated in the drawing is bowed or curved and has one end bearing against the upper flange 16 and has its other end bearing on the upper edge of one of the arms 26. A curved loop or part 44 may be provided on the spring 30 to ride or shiftably bear on the upper edge of the arm 26. In the drawing I have illustrated a preferred manner in which the spring may be effectively held. A lug 32 is stamped out of the upper flange 16 of the body 10 and the spring 30 is received and held between the lug and the upper flange 16 of the body 10 as clearly illustrated in Figs. 4 and 5 of the drawing. The spring 30 is bowed downwardly in a manner to effectively yieldingly urge the arms 26 towards 35 one another and, therefore, urge the soap engaging branches 22 toward one another.

The utility and practicability of the soap holder of my invention will be readily apparent from the foregoing detailed description. The soap holder embodies a minimum number of simple sturdy parts comprising only four principal parts or units, namely the unitary bracket or body 10, the two gripping elements 11 shiftably carried by the body 10 and the means 12 for yieldingly urging the elements into engagement with a cake of soap or the like. The body 10 may be formed or stamped out of a flat blank, making it very cheap and easy to manufacture. The gripping elements in being formed of common round stock can be 50 easily bent into the desired shape and at a nominal cost. It is believed that it will be understood that the improved soap holder of my invention can be mounted in any manner and in any place to be readily accessible to the user.

In operation, the user may pass the cake of soap S upwardly between the gripping branches 22 to a position where the tips 20a of the branches engage the opposite sides of the soap. The user then releases his hold on the soap allowing the 60 branches 22 to support and retain it. The spring 30 urges the branches 22 into gripping engagement with the cake of soap S. The angular relationship of the branches 22 and the force exerted by the spring 30 insure a positive hold on the 65 cake of soap. The branches 22 projecting upwardly and inwardly tend to bite into the soap S and the principal function of the spring 30 is to yieldingly hold the branches in cooperation with the cake of soap.

Regardless of the points at which the tips 20a of the gripping branches 22 engage the sides of the cake of soap S the soap may pivot or swing to have its center of gravity at or below the points of contact of the tips 20a with the soap.

The outer branches 22 of the elements 11 in being spaced outward from the body 10, and in having only point contact with the cake of soap, allow the free pivoting or swinging of the soap 5 to locate itself without interfering with the body. Thus the forces tending to rotate or pivot the cake of soap are equalized.

To remove the cake of soap S the user merely picks up the soap or lifts it from between the 10 gripping branches 22. When moved upwardly the cake of soap freely passes out from between the gripping members 11 and the user is not obliged to contact or engage the soap holder. The soap holder only contacts the soap at two 15 points and, therefore, allows the soap to properly dry after use. It also holds the cake of soap so that it can be readily grasped for use. The cake of soap in being allowed to properly dry does not become softened or slippery and is 20 pleasant to grasp and easy to use.

Having described only a typical form and application of my invention, I do not wish to be limited or restricted to the specific form and application herein set forth, but wish to reserve 25 to myself any modifications or variations that may appear to those skilled in the art or fall within the scope of the following claims.

Having described my invention, I claim:

1. A device of the character described including a body, a pair of L-shaped members carried by the body in spaced relation for pivotal movement to each have one branch project from the body and to have their other branches inclined upwardly and inwardly toward each other to 35 grip a cake of soap passed between them, arms secured to the first mentioned branches, one arm having a curved slot, a pin on the other arm shiftable in the slot, and spring means acting on the arms to urge the second mentioned branches against the soap.

2. A device of the character described including a hollow body, a pair of L-shaped members supported by the body in spaced relation for pivotal movement to each have one branch projecting from the body and to have their other 45 branches inclined upwardly and inwardly toward each other to receive a cake of soap passed upwardly between them, arms on the inner ends of the first mentioned branches within the body, one arm having a curved slot, a pin on the other arm shiftable in the slot to effect simultaneous 50 movement of the members, for limiting their movement and a spring acting on the arms to yieldingly urge the members into cooperation with the cake of soap.

3. A device of the character described including a body, and a pair of spaced substantially L-shaped members formed of elongate rod-like stock, each member having one branch pivotally supported by the body with its pivotal axis 60 normal to the outer face of the body, the other branches of the members being carried on the outer ends of the first mentioned branches to be in spaced relation to the outer face of the body and converging upwardly and inwardly towards each other, the upper ends of said other branches being beveled to have substantially point contact with the opposite sides of a cake of soap passed

between them, and means connecting the members for simultaneous pivotal movement.

4. A device of the character described including a body having a substantially vertical outer face, two members pivotally carried by the body to project from its outer face with their pivotal axes substantially normal to said face, and pointed rod-like gripping fingers on the outer ends of the members in spaced relation to the outer face to the body substantially converging 10 upwardly and inwardly toward one another to have point gripping engagement with a cake of soap introduced between them.

5. A device of the character described including a body adapted to be mounted on a support, two soap gripping elements, means pivotally supporting the elements on the body to have spaced parallel substantially horizontal axes of pivotal movement and to project forwardly beyond the body, and slender upwardly convergent 15 arms on the forward ends of the elements having upper ends shaped to have limited supporting contact with the opposite sides of a cake of soap in a plane spaced from the outer face of the body.

6. A device of the character described comprising a body having a recessed rear side adapted to be arranged against a support, the body having two spaced substantially horizontal openings, gripping elements pivotally supported 20 in the openings to project from the forward side of the body, the gripping elements having upwardly converging branches on their forward ends, and means at the recessed rear side of the body exerting a yielding pivoting force on the 25 elements to urge their branches toward one another to grip an object introduced between the branches.

7. A device of the character described comprising a body having a recessed rear side 30 adapted to be arranged against a support, two elements, means supporting the elements on the body for pivotal movement about spaced substantially horizontal axes and to project from the front side of the body, the elements including 35 branches on their forward ends converging upwardly toward one another, said branches having beveled upper ends adapted to have substantially point contact with an object introduced between them, and means at the rear side of the body exerting a yielding turning force on the 40 elements to urge their branches into holding engagement with the object.

8. A device of the character described comprising, a body adapted to be attached to a support, two elements, each including an inner branch and a slender outer branch angularly related to the inner branch, and means pivotally supporting the inner branches of the elements 45 on the body to project from the front thereof and to pivot about substantially horizontal axes so that the outer branches of the elements converge upwardly to have their upper ends engage and support an object introduced between them, said upper ends engaging the object in a plane 50 spaced a substantial distance from the front of the body.
